ROBERT M. GALLOWAY, OF RICHMOND, INDIANA, ASSIGNOR TO THE NATIONAL AUTOMATIC TOOL COMPANY, OF RICHMOND, INDIANA, A CORPORATION OF INDIANA.

MECHANISM REVERSIBLE WITHOUT BACKLASH ERROR.

Application filed March 24, 1925. Serial No. 17,969.

This invention deals with mechanism in which it is desirable that provision shall be made for "lost motion" of any predetermined extent and in a manner providing for a reversal in motion without shock, i. e., either positively in combination with a gradual accelerating prime-mover or in combination with an abruptly acting reversing clutch; in this instance, the shock absorbing resilient capacity being an inherent characteristic of the lost motion device.

In various types of machines, it is important that a definite amount of motion will be lost at a certain cycle in the operation of the machine; especially where separate lines of transmission involving different degrees of back-lash must be synchronized immediately following a reversal in the direction of action of one or both of the separate transmission. This, for example, is exhibited clearly in certain types of machines for tapping or threading holes.

In such machines, the tool which cuts the threads (the tap) must, of course, have its motion resolved into two components, to wit, that of translation ordinarily termed the "feed" and that of rotation, ordinarily termed the "speed." In short, the compound motion is simply that of an advancing screw. Now, the spindle has this motion and it carries the tap but, in large machines used for other work such as drilling, etc., the component motions of the spindle are varied or changed to meet different requirements by means of change gears appropriately placed in the separate transmission controlling the feed and the speed respectively. But, inasmuch as speed change gearing necessarily provides considerable back-lash and may not always correspond with absolute precision to the particular ratio of movement required for a given "tap," it is usual to resort to a safe-guarding feature which provides a certain amount of allowance, so to speak, in the mounting of the tap on the spindle. In other words, the tap has a certain amount of independent slide on the spindle but no relative rotation with regard to the spindle. This longitudinal play between the tap and the spindle on which it is mounted is provided for by a conventional construction of the tap holder itself.

One of two conventional forms of tap-holders each providing a certain amount of "float" may be used dependent upon existing conditions in the machine tool. For convenience, these two forms will herein-after be referred to as "positive" and "im-positive." The "positive" tap holder is usually used in constructions in which there is more back-lash in the "feed" transmission than in the "speed." This type of tap holder is so constructed that normally the tap-holding portion may move axially away from the shank-portion toward the work but is held against movement in the opposite direction by a suitable retaining wall. Therefore, as the tool-spindle and the tap-holder (and tap carried thereby) are rotated and fed toward the work the tap is fed positively into engagement with the work and must cut a thread in its first rotation after contacting with the work. When this type of tap-holder is used the feed of the tool-spindle is regulated to be just slightly slower than the self-feed of the tap due to the pitch of its teeth and its rotation. Therefore, during the tapping of a hole the tap-holding portion of the tap-holder will over-run the shank and therefore will draw away slightly from the retaining wall, producing clearance between the two. This is permitted by the float provided in the tap holder.

Now should the prime mover, or a master clutch controlling both the "speed" and "feed," be actuated to reverse both transmissions the transmission having the least back-lash will be the first to become effective. As hereinbefore stated, there is more back-lash in the feed than in the speed, and therefore the tap will start to rotate reversely before the spindle and the shank of the tap-holder have begun their reverse feed. Inasmuch as reverse rotation of the tap will cause it to unscrew from the work, which results in axial movement of the tap and its holding portion, most (if not all) of the clearance between the shank and the tap-holding portion will have been taken up before the feed starts its reverse movement. Now it is to be remembered that the spindle feed is regulated to be slower than the self-feed of the tap; therefore, before the tap is completely unscrewed from its

- tapped hole, all of the clearance will have been taken up and the relatively faster self feed of the tap will be attempting to overrun the relatively slower feed of the tap holder. This however is precluded by the contact of the tap-holding portion with the retaining wall of the shank portion, with the result that either the tap or the threads in the work must break.
- 10 This invention rectifies the aforesaid defect by suitably combining with the elements of the machine, as above described, a peculiar lost-motion device which is contrived to introduce (at the time of reversal) sufficient lag in the spindle-rotating transmission to enable the aggregate back-lash in the spindle translating transmission to be taken up and the reverse feed inaugurated before the reverse rotation starts.
- 20 This construction permits the reverse feed to start in advance of the reverse rotation of the tap whereby the relatively faster self-feed of the tap will not overtake the slower spindle feed before the tap has emerged 25 from its tapped hole and therefore no damage will be done either to the tap or to the work.

In the "impositive" tap-holder the "float" is in the direction opposite to that in the "positive" tap-holder; in other words the tap holding portion is permitted to move upwardly on the shank portion away from the work and is normally held against movement on the shank in a direction toward the work by contact between a suitable retaining wall provided by the tap-holding portion and a cooperating part provided by the shank-portion. This type of tap-holder may be used to advantage in 40 tapping machines in which the aggregate back-lash in the spindle rotating transmission is greater than the aggregate back-lash in the spindle feed transmission.

45 In a machine fitted with an impositive tap-holder, when a hole is about to be tapped, the spindle carrying the tap in its lowermost position is being rotated and simultaneously translated towards the work. When the tap first comes into contact with 50 the work, it may not immediately "bite" although the spindle continues to advance. This does no harm, however, because of the longitudinal yield provided as aforesaid but as soon as the tap begins to screw into the work, it continues in a self-feeding manner; being positively rotated by means of the spindle but permitted to have a certain amount of independent feed. It is frequently the case that the tap does not bite 60 into the work until forced into it by spring pressure produced by the take-up of a part of its play on the spindle, but thereafter, the self-feed of the tap will either keep pace with the feed of the spindle or perhaps 65 slightly under-run it thereby slightly sep-

arating the retaining wall and the cooperating portion of the shank.

This mechanism works satisfactorily as described so long as it is feeding "in" but, unless the whole machine be very accurately timed, built and adjusted, a stripping of the threads or at least an injury thereto is likely to occur when the parts are reversed for the purpose of withdrawing the tap from the work. What happens is that there may 70 more accumulated back-lash in the transmission which rotates the spindle than in the separate transmission which feeds it. If so, when the reversal takes place, the feed transmission will take effect on the spindle 75 before the other transmission starts to rotate it reversely.

The consequence is that the spindle and the shank of the tap-holder will start to recede from the work before the tap starts its reverse rotation with the result that all, (or substantially all) of the clearance between the retaining wall and the cooperating part 80 of the shank will be taken up before the tap starts to rotate reversely. Inasmuch as the self feed of the tap is slower than the positive feed of the spindle it will readily be perceived that before the tap has emerged 85 from the tapped hole the positive feed will be acting to withdraw the tap from the hole at a rate faster than the rate of reverse rotation of the tap will permit, with the result that either the tap must break or the threads in the work must strip.

This invention also is adapted to correct 90 this inherent defect in tapping machines in which the excess back-lash is in the spindle rotating mechanism. This is accomplished by embodying a lost-motion device in the spindle feeding transmission whereby, upon reversal, the starting of the feed transmission is delayed sufficiently to enable the tap 95 rotating transmission to become effective first whereupon, through the self-feed of the tap in a reverse direction, additional 100 clearance will be produced between the retaining wall of the tap-holding portion and the cooperating part of the shank. By the time the reverse feed becomes effective there 105 will have been produced more clearance than the differential between the relatively faster spindle feed and relatively slower self-feed of the tap may take up before the tap is unscrewed from the tapped hole, therefore there will be no interference between 110 the power feed and the self-feed of the tap and the tap will be backed out without strain 115 on either the tap or the work.

The type of lost motion connection shown 120 in this application comprises a driving and a driven member with a variable number of floating plates inserted between them. The amount of lost-motion is preferably determined by varying the number of plates included between the driving member and the 125 130

driven member. Lugs, which project from the driving and the driven members and from the floating plates, are arranged to move in the same paths of movement so as to engage each other. The amount of lost motion is not only controlled by the number of floating plates but by the thickness of the lugs on the plates and on the driving and driven members.

When a reversing motor is utilized for reversing a machine of the above indicated type, having a lost-motion connection, it has been found unnecessary to provide the connection with any yielding or resilient means to withstand shocks. The reversing of the direction of rotation of the motor compels it to start from zero speed and gradually increase to the full load speed. Accordingly no shock absorbing means is necessary on the lost-motion connection. However, in case the machine is reversed by mechanism in the form of a jaw-clutch or a similar mechanism, it is very desirable to provide shock absorbing means in the lost motion connection. Preferably resilient means is provided for preventing the direct engagement between the lugs on the floating plates and on the driving and driven members.

Although my invention is described by referring to a machine having an automatically controlled power feed for the taps, it has been found very desirable to provide hand controlled power feed machines with a lost motion connection. The pause in the rotation of the taps, which is caused by the lost motion connection, serves to notify the operator when to change the direction of movement of the head carrying the taps. The lost motion connection has also been found to assist in preventing the breaking of the taps by the internal stress and strains to which they are subjected. The pause in the movement of the taps which is caused by the lost motion connection, permits the stresses and strains which have accumulated in the taps during the tapping operation to dissipate themselves before the reversal in the movement of the taps takes place.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is an elevational view of a tapping machine having a hand-control for the power feeding and provided with a lost motion coupling constructed in accordance

with my invention. Fig. 2 is a front elevational view of an automatic tapping machine constructed in accordance with my invention. Fig. 3 is a side elevational view of the machine shown in Fig. 2. Fig. 4 is a plan view of the machine shown in Fig. 2. Fig. 5 is a sectional view along the line 5—5 of Fig. 4. Fig. 6 is a plan view partly in section along the line 6—6 of Fig. 5. Fig. 7 is a sectional view along the line 7—7 of Fig. 5. Fig. 8 is a sectional view along the line 8—8 of Fig. 2. Fig. 9 is a sectional view along the line 9—9 of Fig. 4. Fig. 10 is a plan view of the differential gear controlling mechanism. Fig. 11 is an elevational view partially in section of a lost motion connection adapted to be used in my machine. Fig. 12 is a sectional view along the line 12—12 of Fig. 13. Fig. 13 is a sectional view along the line 13—13 of Fig. 12. Fig. 14 is an elevational view partially in section of a lost motion connection having shock absorbing elements. Fig. 15 is a sectional view along the line 15—15 of the connection shown in Fig. 14.

Referring to Fig. 1 of the drawings, a hand feed tapping machine is illustrated provided with a lost motion coupling. In a hand feed tapping machine the lost motion coupling serves not only to cushion the machine against the shock produced by an abruptly acting jaw-clutch but also serves to relieve the tap of the stress and strains produced during the tapping operation. The machine shown in Fig. 1, accordingly, serves not only to lengthen the life of the taps but also takes care of the shock produced by the abruptly acting jaw-clutch therein.

The tapping machine shown in Fig. 1, comprises a base 185 from which projects a column or frame 186. The column 186 carries a work-table 187 and a tool-head 188. The work-table 187 is operated on a suitable guideway by means of a hand-crank 189. The head 188, which is mounted on suitable guideways on the column 186, carries a number of tool spindles 190. The taps, which are not illustrated in the drawing, are carried by the spindles 190. The tool spindles 190 are rotated by means of a main spindle 191 which is connected by suitable gearing 195 contained in a casing 196 to a main drive. A lost motion connection 192 having yielding elements incorporated therein is connected between the main spindle 191 and the drill spindles 190. The tool head 188 is raised and lowered by means of a power feed shaft 192 during a drilling operation and is raised and lowered by means of the hand-wheel 197 during a tapping operation.

A complete description and illustration of the gearing 195 contained in the casing 196 for operating the spindle 191 is deemed un-

necessary inasmuch as the tapping machine shown in Figs. 2 to 10 inclusive is completely described and illustrated in detail. The lost motion coupling 192 is described when reference is made to Figs. 14 and 15 of the drawings. In the machine shown in Fig. 1, the head 188 is fed during a tapping operation by means of the hand-wheel 197. The lost motion coupling 192 when combined with a hand-feed machine as shown in Fig. 1 performs three functions for improving the operation of the machine. At the end of the tapping movement and when the holes have been tapped, the reversing of the direction of rotation of the main spindle 191 does not immediately reverse the direction of rotation of the taps by reason of the lost motion included in the coupling 192. The pause thus produced in the rotative movement of the taps permits the stress and strains produced in the taps during the tapping to be dissipated. Moreover the pause thus produced in the rotation of the tap warns the operator of the machine to reverse the direction of movement of the tool head. Furthermore the coupling 192 cushions the shock produced by reversing the direction of rotation of the main spindle 192.

Referring to Figs. 2 to 10, inclusive of the drawings, an automatic tapping machine is illustrated which is constructed in accordance with my invention. The illustrated tapping machine comprises a base member 1 having an upstanding column 2 mounted thereon. The column 2 carries a tool head 3 on suitable guideways 4 and 5. A plurality of taps 6, only one of which is illustrated on the drawings, is carried by the tool head 3. A suitable work table for supporting the work may be provided below the tool head 3. Inasmuch as my invention is not particularly concerned with the table carrying the work, description of such table is omitted from the specification.

A main driving spindle 7 is provided for operating the taps 6 and a lost motion connection 8 is provided between the main driving spindle 7 and the tool head 3. A complete description of the construction and operation of the lost motion connection 8 will be given hereinafter. The main driving spindle 7 is connected to a motor 10 by means of a speed shaft 11 shown in Figs. 2 and 3 of the drawings. The motor 10 not only serves to operate the main driving spindle 7 but also operates a feed shaft 12 for effecting vertical movement of the tool head 3 on the column 2.

The speed shaft 11 has a spline connection with a gear wheel 15 which is supported on a bracket 16. The bracket 16 is supported on the head 3 which carries the main driving spindle 7. Referring to Fig. 9 of the drawings, the gear wheel 15 is shown connected through gear wheels 17, 18 and 19 to a

gear wheel 20 which is mounted on a shaft 21. The shaft 21 carries a second gear wheel 22 which meshes with a gear wheel 23 on the upper end of the main driving spindle 7. The spline connection between the speed shaft 11 and the gear wheel 15 permits the free vertical movement of the tool head 3 and the bracket 16 which is carried upon it. A weight-member (not shown) is provided for counter-balancing the weight of the tool head 3 and thus assist the feed mechanism in operating the tool head along the column. The weight member is connected to the tool head 3 by means of cable 26 which extends over pulleys 27 at the top of the column 2.

A bevel gear wheel 29 is connected to the lower end of the speed shaft 11, as shown in Fig. 3 of the drawings. Such bevel gear wheel 29 meshes with a second bevel gear wheel 30 which is mounted on a shaft 31. The shaft 31 carries another bevel gear wheel 32 which meshes with a bevel gear wheel 33 on a shaft 34. The shaft 34 connects with a main control mechanism which in turn is connected to the main driving motor 10. A bevel gear wheel 35, which is mounted on the shaft 34, meshes with a bevel gear wheel 36 which is carried by a shaft 37 in the transmission mechanism. The shaft 37 projects through a transmission box 38 and carries a gear wheel 39 near the end thereof. The gear wheel 39 meshes with a pinion 40 which is mounted on the armature shaft of the motor 10.

In the above described construction it will be noted the speed mechanism, which rotates the main spindle 7, is directly connected to the motor 10 without the interposition of clutches. The connection between the motor 10 and the main driving spindle 7 comprises the shaft 37, the shaft 34, the shaft 31, the speed shaft 11, and the gear wheels 15, 17, 18, 19, 20, 22 and 23.

The feed shaft 12, which serves to effect the power feed of the head 3 along the column 2, carries a worm member 41 near the upper end thereof. The worm member 41 meshes with a worm wheel 42 which is mounted on a shaft 43. The shaft 43 is provided with bearings in a bracket 44 which is carried by the column 2. The shaft 43 carries a pinion 48 which meshes with the gear wheel 49 on a shaft 50. The shaft 50 is mounted to have sliding movement in the column 2 in order to disconnect the power feed whenever it is desirable to effect feeding movement of the head by hand. A pinion 51, which is formed on the shaft 50, meshes with a gear-wheel 25. The gear-wheel 25 meshes with a rack 52 on the column 2, as shown in Fig. 8 of the drawings. A hand wheel 53 is provided on the end of the shaft 50, as best shown in Figs. 2 and 8 of the drawings, and a spring mem-

ber 54 is mounted on a shaft between the hand wheel 53 and the column 2. The spring member 54 exerts a force tending to hold the shaft 50 in operative engagement with the power feeding mechanism. The shaft is connected to the power feeding mechanism when the gear wheel 49 is in mesh with the pinion 48. If it is desired to effect hand-feeding of the head, the shaft 50 is moved towards the left, as viewed in Fig. 8 of the drawings, to disconnect the gear wheel 49 from the pinion 48.

The lower end of the feed shaft 12 carries a bevel gear wheel 28 which meshes with a bevel gear wheel 57 on a shaft 58, as shown in Fig. 2 of the drawings. The shaft 58 carries a second bevel gear wheel 59 which meshes with a bevel gear 60 on the shaft 61. The shaft 61 connects with the main motor 10 by means of the main transmission mechanism above referred to. A shaft 63 in the transmission mechanism carries a bevel gear wheel 64 which meshes with a bevel gear wheel 65 on the shaft 61. The shaft 63 carries a differential gear mechanism 66 intermediate the ends thereof, as shown in Fig. 5 of the drawings. The differential gear mechanism comprises two end bevel gears 67 and 68 which respectively carry two spur gear wheels 69 and 70. The bevel gear wheels 67 and 68 are rotatably supported on the shaft 63 by means of suitable bushings and mesh with two bevel gear wheels 71 and 72 which are rotatably mounted on the central portion 73 of the differential gear mechanism. The central portion of the differential gear mechanism is keyed to the shaft 63. The differential gear mechanism 66, as above described, is old and well known and varies the speed of rotation of the shaft 63 in accordance with relative speed of the two spur gear wheels 69 and 70. If the spur gear wheel 70 is held stationary and the spur gear wheel 69 is rotated at a predetermined speed, then the shaft 63 is rotated in the same direction and at half the speed of rotation of the gear wheel 69. If the gear wheel 70 is rotated in a reverse direction and at a different speed as compared with the gear wheel 69, then the shaft 63 is rotated at one half the difference in rotation of the gear wheels 69 and 70. The spur gear wheel 69 is rotated at a faster rate than the spur gear wheel 70 and thus no change in the direction of rotation of the shaft 63 is effected by the differential gear mechanism. When the gear wheel 70 is held stationary, the shaft 63 is rotated at a relatively rapid rate to effect traversing movements by the head. When the gear wheel 70 is rotated simultaneously with the gear wheel 69, the shaft 63 is rotated at a much slower rate to effect feeding movement by the head. The direction of rotation of

the shaft 63 and accordingly the direction of movement of the head is controlled by the motor.

The spur gear 69 meshes with a gear wheel 75 which is keyed to a shaft 76 having suitable bearings in the transmission box 38. The spur gear wheel 70 is connected to a gear wheel 77 by means of an idler gear 78. The idler gear 78 is mounted on a shaft 79 carried by the box 38. The gear wheel 77 is keyed to a bushing 80 which is rotatably mounted on the shaft 76, as shown in Figs. 4 and 5 of the drawings. The bushing 80 also carries one member 81 of a clutch mechanism 82. The clutch member 81 is splined to the bushing 80 and is provided with clutch teeth 83 which are adapted to mesh with similar clutch teeth on the other member 84 of the clutch mechanism 82. The clutch member 84 is keyed to the shaft 76. A lever 85, which is fixedly mounted on a shaft 86, is provided for shifting the clutch member 81 along the sleeve 80 to control the engagement of the clutch member 81 with the clutch member 84. A pin 87, which is secured to the lower end of the lever 85, projects into a groove 88 formed in the member 81. A second lever 89, which is fixedly mounted on the shaft 86, carries a pin 90 which projects into the groove 88. The upper end of the lever 85 carries a pin 91 which engages a collar 92 slidably mounted on a shaft 93. A U-shaped member 94 is slidably mounted on the shaft 93 by means of a set screw 95 and spring members 96 and 97 are mounted on the shaft between the ends of the U-shaped member 94 and the collar member 92. The member 94 is operated by means of a lever 98 which extends to the front of the box 38 and is pivotally connected to a bell-crank lever 99. The lever is secured to the U-shaped member 94 by means of the bolt 95. The bell-crank lever 99 is pivotally supported at 100 and in turn is connected to a link 101. The link 101 is connected to a lever 102 which is operated by a hand-lever 160 as shown in Figs. 3, 4 and 10, to control the operation of the clutch mechanism 82.

The lever 98 which controls the clutch mechanism 82 is also operated automatically in accordance with the movement of the tool head. A rod 161 as shown in Figs. 3 and 10 of the drawings is so supported on the column 2 as to have a limited movement in accordance with the movement of the head. A lug 162 on the head 3 is adapted to engage a yielding pin 163 on the rod 161 to effect movement of the rod. When the rod 161 is moved to the limit of its movement the pin 163 permits the lug 162 to pass over it. Upon the return movement of the lug 162 the pin 163 is again engaged to move the rod 161 in a reverse direction. The rod 161 has rack teeth formed on its lower end which mesh with a pinion 165 on a shaft 166. The

shaft 166 carries a second gear wheel 167 which engages a rack 170 on the lever. In such manner the clutch 82 is controlled in accordance with the movement of the head. The head is moved downwardly at a rapid rate until the taps are about to engage the work. At such time the lug 162 operates the rod 161 to engage the clutch 82 and effect a slow-feeding movement. At the end of the 10 tapping operation the motor is reversed from the controller 110 by means of the lug 112 engaging the lever 111. When the tap clears the work the lug 162 operates the rod 161 to disengage the clutch 82 and effect a rapid 15 traverse movement upwardly of the head.

The clutch member 81 is provided with two projecting lugs 105 and 106 one of which is adapted to engage a stop member 107 when the clutch mechanism 82 is in the 20 disengaged position. The stop member 107 is secured to the box 38 as shown in Fig. 6 of the drawings and serves to prevent rotation of the clutch member 81 and the gear wheels 77 and 70 when the clutch mechanism 82 is 25 disengaged and a rapid traverse operation is being effected. When the clutch mechanism 82 is engaged, the projecting lugs 105 and 106 are moved so as not to engage the stop member 107. Accordingly, it is apparent in 30 one position of the clutch mechanism the gear wheel 70 is held stationary to rotate the shaft 63 at half the speed of the gear wheel 69 and in the opposite position of the clutch mechanism 82 the gear wheel 70 is rotated in 35 a direction opposite to the direction of rotation of the shaft 69 and at a slightly different rate to effect rotation of the shaft 63 at half the difference in speed of rotation of the gear wheels 69 and 70.

In the above described mechanism it will 40 be noted a shifting movement of the lever 98 serves to effect a movement of translation of the U-shaped member 94. One end of the springs 96 and 97 engages the collar member 45 92 for operating the lever 85 which controls the clutch member 81. The spring members 96 and 97 serve to effect a yielding engagement between the clutch teeth on the clutch members 81 and 84.

The shaft 76 carries a gear wheel 103 which meshes with a gear wheel 104 on the shaft 37. The gear wheel 103 is keyed to the shaft 76 and serves to maintain the shaft 76 in rotation whenever the motor 10 is in 50 rotation. Thus, it is apparent when the clutch 82 is disengaged, the shaft 63 is operated at a predetermined speed which is half the speed of rotation of the gear wheel 69. However, upon engaging the clutch the 55 gear wheel 70 is operated at a slightly different speed as compared with the gear wheel 69 and in a reverse direction. In such a case, the shaft 63 is operated at half the difference in speed of rotation of the gear 60 wheels 69 and 70. The slow speed of the

shaft 63 is used during the power feeding of the head 3. The fast speed of shaft 63 is used during the traversing movement of the head either towards or away from the work depending on direction of rotation of the 70 motor.

The motor 10, which controls the rotation of the main spindle 7 and the movement of the head 3 in the above indicated manner, is governed by a control box 110. A control lever 111 on the controller 110 is operated by dogs 112 and 113 on a rod 114. The rod 114 is secured to the head 3 and accordingly operates the controller 110 in accordance with the movement of the head. The controller serves to reverse the direction of rotation of the motor 10 in order to reverse the direction of rotation of the main driving spindle 7 and the direction of movement of the head 3. Thus, at the completion of a 85 tapping operation the controller 110 is operated to raise the head from the work and at the same time to reverse the direction of the rotation of the main driving spindle, in order to permit the withdrawing of the taps 90 from the work.

It will be noted in the above described machine, a single source of power is provided for operating two separate branches of a transmission mechanism. One branch, as above described, effects rotation of the taps on the machine and the other branch serves to feed the head which carries the taps. Inasmuch as the two branches of the transmission mechanism are interconnected 100 no trouble is encountered during the tapping operation to maintain the linear movement and the rotary movement of the taps in correct relation. However, upon completion of the tapping operation, it is necessary to reverse not only the direction of rotation of the taps but also to reverse the linear movement of the taps. Each of said branches in the transmission system have more or less back-lash and it is necessary to take care of such back-lash if the taps are to be withdrawn from the work without injuring the threads which have been cut. It is not only necessary to have the linear movement and the rotative movement effected in a predetermined ratio during the withdrawing movement but it is also necessary to insure that the self-feed of the tap and the movement of the tap-holder effected by the feed mechanism will not conflict. The branch 110 of the transmission mechanism which operates the power feeding of the head, generally contains more back-lash than the branch of the transmission system which effects rotation of the taps. Accordingly, a predetermined amount of lost motion or back-lash is inserted in the branch of the transmission system which effects rotation of the taps. Thus, it is apparent in a machine constructed in accordance with my invention, 125 130

a compensation for back-lash is made rather than an attempt to do away with the back-lash which always is present. Although my invention has been described by means of a machine for operating taps, it is apparent that the principle involved in the invention is equally applicable to any machine where movement is effected in accordance with a predetermined spiral. In the tapping machine described, the head and the main spindle are operated in accordance with the thread on the taps. It is apparent that other machines operated in accordance with a predetermined spiral or thread may practice the invention disclosed in this application.

Referring to Figs. 11, 12 and 13 of the drawings, the lost motion connection 8, inserted in the branch of the transmission line 20 for rotating the taps, is illustrated in detail. The lost motion connection comprises a driven member or sleeve plate 120 which is fixedly mounted on a driven shaft 121. Preferably suitable keys 122 and a pin 123 are provided for securing the sleeve plate to the shaft 121. The sleeve plate 120 is provided with a hub portion 124 upon which are mounted bushings 125 and 126. The bushings 125 and 126 respectively carry two floating plates 127 and 128. Adjacent to the floating plate 127 is mounted a driving member 129 which is secured to the main driving spindle 7. The driving member 129 is secured to the main spindle 7 by means of a suitable key member 130. The floating plates 127 and 128 and the disk portion of the driving member 129 are surrounded by a casing or housing 131 which is secured to the sleeve plate 120 by means of a screw 132. The casing or housing 131 serve to hold suitable lubricating material, as for example light grease or heavy oil, in engagement with the driving and driven members and the floating plates 127 and 128. An opening 133 is provided for inserting the lubricating material in the housing.

The sleeve plate 120 is provided with a projecting lug 135 which is adapted to engage a projecting lug 136 on the floating plate 128. The floating plate 128 is provided with a second projecting lug 137 which is positioned in the path of movement of a lug 139 on the floating plate 127. The floating plate 127 is provided with a second projecting lug 140 which is positioned in the path of movement of a lug 141 projecting from the driving member 129.

Referring to Fig. 11 of the drawings, it will be noted motion is directly transmitted from the main driving spindle 7 to the driven shaft 121 when the lugs 135, 136, 137, 139, 140 and 141 are positioned as indicated and the spindle 7 is rotated in the direction of the arrow α . Upon rotation of the spindle 7 in a reverse direction a predetermined lost

motion is provided before rotation of the driven shaft 121 is effected. The lost motion produced upon reversing the direction of rotation of the spindle 7 depends upon the number of floating plates provided in the connection and upon the width of the projecting lugs on the floating plates and on the driving and driven members. The rotation of the spindle 7 and the driving member 129 in a reverse direction effects a complete rotation less the thickness of the projecting lugs 141 and 140 before any movement of the floating plate 127 is effected. When the lug 141 engages the opposite side of the lug 140, the floating plate 127 is rotated through a complete rotation less the thickness of the lugs 139 and 137 before any movement of the floating plate 128 is effected. When the lug 139 engages the opposite side of the lug 137, the floating plate 128 is rotated through a complete rotation less the thickness of the lugs 137 and 139 before any movement of the driven member 120 is effected. When the projecting lug 136 engages the opposite side of the lug 135, the driving shaft or spindle 7 is directly connected to the driven shaft 121.

The amount of lost motion produced by the above described connection is equal to three rotations of the main spindle 7 less the thickness of the projecting lugs. The amount of lost motion may be varied by changing the thickness of the lugs and by varying the number of the floating plates. Preferably the lost motion is controlled by varying a number of floating plates provided in the connection.

The connection disclosed in Figs. 11, 12, and 13 of the drawings is preferably used in a machine that is not reversed by an abruptly acting jaw clutch mechanism. The above described lost motion connection works very satisfactory in a machine having a reversing motor for changing the direction of rotation of the various moving parts as disclosed in this application. In case an abruptly acting clutch mechanism is combined with a lost motion connection, some resilient absorbing means must be provided between the various projecting lugs on the plates in the connection.

In Figs 14 and 15 is disclosed a lost motion connection which is provided with resilient means adapted to withstand the shock such for example as is produced by an ordinary quick-acting jaw clutch mechanism. The connection shown in Figs. 14 and 15 comprises a sleeve or driven member 144 which is fixedly mounted on a driven shaft 145. A hub portion 146 on the driven member 144 carries a bushing 147. The bushing 147 supports a floating plate 148 which carries two floating rings 149 and 150. A driving member 151, which is mounted on the main driving spindle 7, is positioned adjacent to the

floating plate 148. The floating plate 148 is adapted to be operated by the driving member 151. A lug 152, which projects from the sleeve member 144, is positioned in the path of movement of a lug 153 on the floating plate 148. A second projecting lug 154 on the floating plate 148 is positioned in the path of movement of a lug 155 on the driving member 151. Two spring members 156 and 157, which are shown in Fig. 15 of the drawings, are positioned on opposite sides of the projecting lug 154 on the floating plate. Spring members similar to the spring members 156 and 157 are positioned on opposite sides of the lug 153 which project from the floating plate. The floating ring 150 serves to hold the two spring members 156 and 157 in position to be engaged by the lugs 154 and 155 and the floating ring 149 serves to hold the two spring members associated with the lugs 152 and 153 in position to be engaged by such lugs. A casing or housing 156^a is provided for enclosing the coupling and is preferably secured to the sleeve member 144 by means of a set screw 158.

Assuming the driving spindle 7 to be rotating in a clockwise direction, the lug 155 projecting from the driving member 151 compresses the spring 156 between it and the lug 154 projecting from the floating plate 148. The lug 153 projecting from the opposite side of the plate 148 compresses the spring between it and the lug 152 which projects from the sleeve member 144. The spring members serve to cushion the connection against an abrupt shock such as is produced by a quick-acting reverse mechanism. Upon reversing the direction of a rotation of the spindle 7 the lug 155 is moved to the dotted line position shown adjacent to the spring member 157 in Fig. 15 of the drawings. The counter-clockwise rotation of the driving spindle compresses the spring member 157 between it and the lug 144 projecting from the plate 148. It will be noted, however, that before the lug 155 engages the spring member 157, the spindle 7 and the driving member 151 have made one revolution less the thickness of the lugs 154 and 155 and the length of the spring member 157. The compressing of the spring 157 serves to cushion the shock produced by an abrupt reversing mechanism. The plate 148 is rotated through one revolution less the thickness of the lugs 152 and 153 and the length of one of the spring members before effecting any movement of the driven member 144. A fixed and rigid connection between the spindle 7 and the driven shaft 144 is not effected until after complete compression of the springs which are located between the lugs on the driving and driven members and on the floating plate.

Without further analysis, the foregoing

will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:—

1. A machine-tool combining a prime-mover; a tool-supporting spindle; a transmission therebetween comprising two branches, the one for rotating and the other for translating said spindle; a reversing means for said transmission; and a lost-motion coupling controlling the spindle-rotating branch, said lost-motion coupling providing a lag so related to the aggregate back-lash of the transmission between the reverser and the spindle as to defer the reverse turning of said spindle until it has begun its reverse translation.

2. A machine-tool combining a member mounted to be simultaneously given two distinct movements; a power-driven transmission comprising two branch-line transmissions, the one for imparting the one movement and the other for imparting the other movement; a reversing mechanism for said transmission; and a lost-motion coupling controlling one of said branch-line transmissions, said lost-motion coupling being constructed to provide a lag not less than the excess of the aggregate back-lash of the other branch-line transmission over the aggregate back-lash of the branch-line transmission embodying said coupling.

3. A tapping machine combining a spindle adapted to be simultaneously translated and rotated; a motion-reverser; two transmission means operated thereby, the one for translating and the other for rotating said spindle; and a lost-motion coupling in the rotation-imparting transmission means adapted to delay said means from reversely operating said spindle until said other means has started reversely to translate said spindle.

4. In a machine-tool, the combination comprising a cutting tool; a work member to be operated on by said cutting tool; feed mechanism for effecting relative linear movement between the work member and the tool; speed mechanism for effecting relative rotation between the cutting tool and the work member, said speed mechanism being operated in timed relation to said feed mechanism; and a back-lash compensating

mechanism for insuring the starting of the speed mechanism and the feed mechanism in a predetermined order upon reversal of such mechanisms.

5. In a machine-tool, the combination comprising a cutting tool; a work member to be operated on by said cutting tool; feed mechanism for effecting relative linear movement between the cutting tool and the 10 work member; speed mechanism for effecting relative rotation between the cutting tool and the work member, said linear and rotative movements being effected in accordance with a predetermined thread; and 15 a lost motion connection embodied in the one of said mechanisms normally having the least back-lash, to permit the other of said mechanisms to be rendered effective first upon reversal of the feed and speed mechanisms.

6. In a machine-tool, the combination comprising a cutting tool; a work member connected to said cutting tool by a thread; speed mechanism for effecting relative 25 rotation between the work member and the cutting tool; feed mechanism for effecting relative linear movement between the cutting tool and the work member, said linear movement being effected in accordance with the 30 thread connection between the work member and the cutting tool; and mechanism compensating for back-lash to maintain the work member and the cutting tool in correct relation to each other upon reversal of the 35 feed mechanism and the speed mechanism.

7. In a machine-tool, the combination comprising a cutting tool; a work member adapted to be operated on by said cutting tool; feed mechanism for effecting relative 40 linear movement between the work member and the cutting tool; speed mechanism for effecting a relative rotative movement between the cutting tool and the work member, said feed mechanism and the speed 45 mechanism being interconnected to maintain a predetermined ratio between the linear movement and the rotative movement; and back-lash compensating mechanism for insuring the starting of the linear movement and the starting of the rotative movement in correct relation upon reversal of the feed mechanism and the speed mechanism.

8. In a machine-tool, in combination, a 50 tool; mechanism to rotate said tool; mechanism to feed said tool bodily during its rotation; a single reversing means for simultaneously reversing the tool feeding and rotating mechanisms; and a delayed action device embodied in one of said mechanisms to produce a dwell therein to cause the other of said mechanisms to become effective first after the actuation of said reversing means.

9. In a machine-tool, the combination comprising a spindle; speed mechanism for 55 rotating said spindle; feed mechanism op-

erated in accordance with the operation of the speed mechanism for feeding said spindle; and a back-lash compensating mechanism between the speed mechanism and the spindle for preventing rotation of the spindle until after the back-lash in the feed mechanism is taken up.

10. In a machine-tool, the combination comprising a plurality of spindles; speed mechanism for rotating said spindles; feed 70 mechanism operated in accordance with the operation of the speed mechanism for feeding said spindles, means for reversing the direction of rotation of the speed mechanism and of the feed mechanism; and mechanism between the speed mechanism and the spindles for preventing the rotation of the spindles in a reverse direction until the back-lash in the feed mechanism is taken up.

11. In a machine-tool, the combination comprising a tap; speed mechanism for rotating said tap in a forward and in a reverse direction; feed mechanism for moving the tap longitudinally in accordance with the 80 operation of the speed mechanism; and mechanism for preventing rotation of the tap in a reverse direction by the speed mechanism until the back-lash in the feed mechanism is taken up.

12. In a machine-tool, the combination comprising a tool adapted to be rotated and to be moved longitudinally in accordance with the rotation thereof; speed mechanism for rotating said tool in a forward and in a reverse direction; feed mechanism for moving the tool longitudinally in accordance with the operation of the feed mechanism and in a direction in accordance with the direction of the tool rotation; and mechanism for compensating for the back-lash in the feed mechanism upon reversal of the speed mechanism.

13. In a machine-tool, the combination comprising a tool head movable on the machine frame and having a number of taps rotatably mounted thereon; a main spindle for rotating said taps; a speed mechanism for operating said spindle; a feed mechanism for operating said tool head in accordance with the operation of said speed mechanism; and a back-lash compensating mechanism connected to said spindle for insuring the taking up of the back-lash in the feed mechanism prior to the rotation of the taps mounted on said tool head.

14. In a machine-tool, the combination comprising a tap; speed mechanism for effecting rotation of said tap in a forward and in a reverse direction; feed mechanism for effecting linear movement of the tap in accordance with the rotative movement thereof, the direction of linear movement being varied in accordance with changes in the direction of rotation of the tap; and a lost-

motion coupling between the speed mechanism and the tap for preventing rotation of the tap in a reverse direction until the back-lash in the feed mechanism has been taken up.

15. In a machine-tool, the combination comprising a tap; a work member adapted to have a thread formed therein by said tap; speed mechanism for effecting rotation of said tap in a forward and in a reverse direction; feed mechanism for effecting linear movement of the tap in accordance with the rotative movement thereof, the direction of linear movement being varied in accordance with changes in the direction of rotation of the tap; and a lost-motion coupling between the speed mechanism and the tap to insure the starting of the linear movement and the rotative movement of the tap in correct relation upon withdrawal of the tap from the work.

20. In a machine-tool, the combination comprising a tap; a work member adapted to have a thread formed therein by said tap; speed mechanism for effecting rotation of said tap in a forward and in a reverse direction; feed mechanism for effecting linear movement of the tap in accordance with rotative movement thereof; and a lost-motion coupling in one of said mechanisms to insure the starting of the feed mechanism and the speed mechanism in correct relation upon withdrawal of the tap from the work.

25. In a machine-tool, the combination comprising a tap; a work member adapted to have a thread formed therein by said tap; tap operating mechanism for effecting a feeding and a rotative movement of said tap to form a thread in said work member, said mechanism being operable in a reverse direction to withdraw the tap from the work; and a back-lash compensating mechanism for insuring the starting of the rotative movement and the linear movement of the tap in corrected relation upon reversal of said tap operating mechanism.

30. In a machine-tool, the combination comprising a tap; a work member adapted to have a thread formed therein by said tap; tap operating mechanism for effecting a feeding and a rotative movement of said tap to form a thread in said work member, said mechanism being operable in a reverse direction to withdraw the tap from the work; and a lost-motion coupling inserted in said mechanism for preventing rotation of the tap in a reverse direction until linear movement in a reverse direction is effected.

35. In a machine-tool, the combination comprising a tool head movable along the frame of the machine; a tap carried by said tool head; a spindle for rotating said tap; speed mechanism comprising a system of gears for rotating said spindle in a forward and in a reverse direction; feed mechanism

comprising a system of gearing connected to said speed mechanism for moving said tool head along the machine frame according to the operation of said speed mechanism; and a lost-motion coupling for so connecting the speed mechanism to the tap spindle as to prevent rotation of the tap in a reverse direction until the back-lash in the feed mechanism has been taken up.

40. In a machine-tool, the combination comprising a tool head movable along the frame of the machine; a tap carried by said tool head; a two-part spindle of which one part is connected to rotate said tap; speed mechanism comprising a system of gearing connected with the other part of said spindle for rotating said spindle in a forward and in a reverse direction; feed mechanism comprising a system of gearing connected to said speed mechanism, said feed mechanism serving to move the tool head along the frame in a direction corresponding to the direction of rotation of the tap spindle; and a lost motion connection between the two parts of said spindle for preventing rotation of the tap in a reverse direction until the back-lash in the feed mechanism has been taken up.

45. In a machine-tool, the combination comprising a tool head movable along the frame of the machine; a plurality of taps carried by said tool head; a spindle for rotating said taps; speed mechanism connected to a source of power and comprising gearing for rotating the spindle in a forward and in a reverse direction; feed mechanism comprising gearing connected to said speed mechanism, and operated in timed relation thereto, for raising and lowering the tool head; and a lost motion connection between said spindle and the taps, said connection serving to prevent reverse rotation of the taps until the back-lash in the feed mechanism is taken up.

50. In a machine-tool, the combination comprising a tap; a tool head carrying said tap and movable along the frame of the machine; a spindle adapted to effect rotation of said tap; a work member adapted to have a thread formed therein by said tap; speed mechanism for effecting rotation of said spindle; feed mechanism for effecting linear movement of said tool head and connected to said speed mechanism in order to maintain the ratio between the rotative movement and the linear movement to correspond to the thread on said tap; and back-lash compensating mechanism for preventing rotation of the tap in a reverse direction for withdrawal from the work until after the back-lash in the feed mechanism is taken up.

55. A machine tool combining a rotatable cutting tool; a spindle for rotating said cutting tool; mechanism for rotating said spindle in forward and in reverse direc-

tions; means active independently of the rotation of the spindle to feed the spindle axially; and a lost motion coupling embodied in said spindle rotating mechanism 5 for producing a pause of predetermined duration in the rotative movement only of the tool when the mechanism is reversed.

24. A multiple spindle tapping machine combining a plurality of rotatable tap-spindles; mechanism including a single reversible drive shaft for rotating said spindles in forward and in reverse directions; mechanism for positively feeding said spindles axially and a positively acting lost-motion coupling 15 inserted between said drive shaft and said spindles for producing a predetermined lag in the reversing of the rotation of the spindles upon reversing the rotation of said drive shaft.

25. In a machine-tool, the combination comprising a work support; a rotatable member; mechanism for rotating said member in a forward and in a reverse direction; mechanism for effecting relative feeding 25 movements in reverse direction between the rotatable member and the work on said work-support; and a lost-motion coupling embodied in one of said mechanisms to delay the action of that mechanism when the two 30 mechanisms are reversed, said coupling having resilient means for cushioning the shock produced by the reversal of said mechanism.

26. In a tapping machine, the combination comprising a prime mover; a rotatable and translatable tool-spindle adapted to carry a tap; a forward and a reverse spindle rotating drive between said prime mover and said tool-spindle; a forward and a reverse feed for said tool spindle independent 35 of its rotating means; and a lost-motion device embodied in said rotating means intermediate the prime mover and the tool spindle to produce a predetermined delay in the 40

rotation of the spindle when the reverse drive is rendered effective. 45

27. In a tapping machine, the combination comprising a prime mover; a rotatable and translatable tool-spindle adapted to carry a tap; a forward and a reverse spindle rotating drive between said prime mover and 50 said tool-spindle; a forward and a reverse feed for said tool spindle independent of its rotating means; and a lost-motion coupling embodied in said drive intermediate the prime mover and the tool spindle to delay 55 the rotation of the spindle when the reverse drive is rendered effective, said coupling having resilient members for cushioning the shock produced upon the inauguration of 60 the reverse drive.

28. In a multiple tapping machine, the combination comprising a plurality of taps; a two-part main spindle; mechanism for rotating said main spindle; means for operating said mechanism in forward and reverse 65 directions; a tool-spindle intermediate the main spindle and each of said taps; and a lost motion connection between the parts of the main spindle to produce a predetermined delay in the rotation of the tool-spindles 70 when the main spindle rotating mechanism is reversed.

29. In a tapping machine, the combination comprising a tap; a main spindle for rotating said tap; mechanism for rotating 75 said spindle; means for operating said mechanism in a forward and in a reverse direction; and a lost motion coupling for connecting said spindle to the tap, said coupling 80 having resilient members for cushioning the shock produced upon reversing said mechanism.

In witness whereof, I have hereunto subscribed my name.

ROBERT M. GALLOWAY.
